UNITED STATES PATENT OFFICE.

WILLIAM T. BARRATT, OF BENNINGTON, VERMONT, ASSIGNOR TO CHARLES S. KEHOE,
ANNIE COOPER, AND ALEXANDER J. COOPER, EXECUTORS OF CHARLES COOPER,
DECEASED, LATE OF BENNINGTON, VERMONT.

CIRCULAR-KNITTING MACHINE.

1,230,837.

Specification of Letters Patent. Patented June 26, 1917.

Original application filed February 11, 1916, Serial No. 77,782. Divided and this application filed July 24, 1916. Serial No. 110,829.

To all whom it may concern:

Be it known that I, WILLIAM T. BARRATT, a citizen of the United States, residing at Bennington, in the county of Bennington 5 and State of Vermont, have invented new and useful Improvements in Circular-Knitting Machines, of which the following is a specification.

This invention relates to improvements in 10 circular knitting machines, especially relating to the sinker wheel and the supporting structure therefor and it is divided out of the application made by me entitled "Circular knitting machine," filed February 11, 15 1916, Ser. No. 77,782.

The object of the invention is to conserve 20 the space around the outside of the knitting cylinder so that as many different feeds as possible may be introduced into one machine, thus increasing the output of said machine, and also to render the sinker wheel device capable of ready adjustment relatively to the cylinder as a unit, including not 25 only the sinker wheel and its rotary support but the spring and stop by which said sinker wheel is positioned relatively to the knitting machine and its needles, whereby said sinker wheel and the support and spring can be adjusted as one piece relatively to the needles 30 of the knitting machine and thus keep the relative location of the sinker wheel, the stop and the spring by which the sinker wheel is held against the stop unchanged.

The invention is an improvement upon 35 the sinker wheel and supporting structure therefor disclosed in U. S. Letters Patent Nos. 917,989 and 1,003,085.

The invention consists in the combination 40 and arrangement of parts set forth in the following specification and particularly pointed out in the claims thereof.

Referring to the drawings:

Figure 1 is a detail plan illustrating my 45 improved sinker wheel and stand in connection with a portion of the lower needle cylinder and bed-plate.

Fig. 2 is a sectional elevation taken on line 2—2 of Fig. 1.

Fig. 3 is a front elevation of said sinker 50 wheel and stand showing the same in connection with the upper and lower needle cylinders, the needles being omitted.

Like numerals refer to like parts throughout the several views of the drawings.

In the drawings, 5 is the primary needle 55 cylinder and 6 the secondary needle cylinder. 7 are the needles of the primary cylinder and 8 the needles of the secondary needle cylinder. The primary needle cylinder 5 is fastened to a running ring 9 which is 60 rotatable upon the lower bed-plate 10. Said running ring and primary needle cylinder are rotated by an annular gear 11 which is fast to the running ring 9 and is driven by a gear fast to a vertical shaft (not shown 65 in the drawings). A reciprocatory motion is imparted to the primary and secondary needles in a manner well known by means of needle cams 39 and 40 which are fastened, respectively, to the lower bed plate 10 and 70 the upper bed plate 13.

The secondary cylinder 6 is fastened to a running ring 12 which is rotatably mounted in the upper bed plate 13 and has fastened to its upper face an annular gear 14 which 75 is driven by a gear fast to said vertical shaft (not shown in the drawings).

In each of the feeds there is a rotary sinker wheel 15 which is substantially the same in construction as the sinker wheel illustrated in my U. S. Letters Patent No. 1,003,085. This sinker wheel is rotatably mounted upon a stud 16 which is fastened to a rocker frame 17. The rocker frame 17 is rotatably mounted upon a standard 18 fast 80 to the lower bed-plate 10 by means of screws 19 which have screw-threaded engagement with the lower bed-plate 10 and project through slots 20 in the standard 18, whereby said standard is rendered adjustable upon 90 the lower bed-plate 10. It will be noted that the sinker wheel 15 is eccentric to the axis of the rocker frame 17. The sinker wheel 15 is provided with sinkers 21 which are slidable radially upon said sinker wheel 95 and between the primary needles 7, movement being imparted to said sinkers by a cam 23.

A rotary motion is imparted to the sinker wheel 15 by a gear 24 fast thereto and meshing into the primary needles 7, whereby said gear is rotated.

The rocker frame 17 has an arm 25 fast thereto which extends radially outward from said rocker frame and terminates in a 105 vertically disposed portion 26. Said vertically disposed portion, when the parts are in operative position as illustrated in Fig. 1,

bears against a stop 27. Said stop also acts as a clamp and by means of screws 28 clamps one leg 29 of a U-shaped spring 30 to the standard 18. The other leg 31 of said U-shaped spring 30 is bent at its free end to form a V, one side 32 of said V bearing against the arm 25 and holding it against the stop 27 when the parts are in operative position, the other side 33 of said V bearing against the opposite side of said arm when holding the sinker wheel 15 out of operative position with relation to the needles. The base 34 of said U-shaped flat spring bears against a stop-screw 35 which has screw-threaded engagement with the stop 27.

When the parts are in the position illustrated in Fig. 1 the sinkers are in operative relation to the needles of the primary cylinder and the sinker wheel is held yieldingly in this position by the spring 31 which bears against the arm 25 and holds said arm 25 against the stop 27, with the sinker wheel and its sinkers in operative position relatively to the needles of the primary needle cylinder. When, however, anything happens to prevent the free rotation of the sinker wheel, such as the yarn bunching on the needles or the needles becoming bent, then the sinker wheel is moved in the same general direction as the portion of the needle cylinder adjacent thereto and the sinkers are moved out of operative position with relation to the needles, this operation being substantially the same as described in my Patent No. 1,003,085, and as the sinker wheel moves out of operative position relatively to the needles the leg 31 of the spring 30 is sprung outwardly by the arm 25 until the portion 33 of said flat spring contacts with the right hand side of the arm 25 (Fig. 1), when it will be evident that said arm 25 will be held by said flat spring in such a position that the sinker wheel will be held out of operative position relatively to the needles.

The stop-screw 35 supports the flat spring 30 while the arm 25 is moving toward the left and past the V-shaped portion of the flat spring. Otherwise said flat spring would bend from the point where it is clamped between the stop 27 and the standard 18, the whole end of said spring swinging with the arm 25, but as the base 34 is supported against the stop-screw 35, the action of said flat spring, when the arm 25 is moved to the left (Fig. 1), is to spring outwardly away from the standard 18 and allow the arm 25 to pass from one side of the V-shaped portion of said flat spring to the other. By this construction a light and flexible flat spring can be employed which will firmly hold the sinker wheel in position but yet will allow it to yield readily when there is a needle bent or when a bunch of yarn collects on the needles.

The sinker wheel is thrown back into

operative position by the operator who springs the leg 31 outwardly to allow the arm 25 to be pushed against the stop 27, when the leg 31 of the flat spring is released and assumes the position illustrated in Fig. 1 with the parts locked in position ready for operation. When the sinker wheel is moved in the general direction of that portion of the needle cylinder adjacent thereto, the vertical portion 26 of the arm 25 will engage an arm 36 which is fastened to a circular slide 37. Said circular slide is arranged to slide in suitable guide brackets 38 fast to the lower bed plate 10. Said slide when so moved operates a stop mechanism to stop the machine.

The sinker wheel operates in substantially the same manner as set forth in said Patent No. 1,003,085, but it will be understood that when it is desired to adjust the sinker wheel circumferentially of the needle cylinders or in any direction in order to change the location of the sinkers relatively to the needles and needle cams, the relative position of the sinker wheel and its sinkers to the stop 27 and the U spring 30 will not be changed, so that said stop, U spring and sinker wheel can all be moved as a unit keeping their relative positions to each other unchanged.

To adjust the sinker wheel circumferentially of the needle cylinders for the purposes hereinbefore set forth the screws 19 are loosened and the standard 18 moved to the desired position, whereupon the screws 19 are again tightened to hold said standard and the parts supported thereby in position.

Having thus described my invention, what I claim and desire by Letters Patent to secure is:

1. A knitting machine having, in combination, a needle carrier with needles thereon, a bed plate upon which said needle carrier is rotatably mounted, a standard adjustably mounted on said bed plate, a rocker frame pivoted to said standard, a sinker wheel equipped with sinker blades journaled to rotate upon said rocker frame and eccentric to the axis thereof and yielding means fast to said standard adapted to hold said rocker frame in position and prevent the same from rotating while said sinker blades are in operative engagement with said needles, whereby said sinker wheel, rocker frame and yielding means may be simultaneously adjusted relatively to said needle carrier.

2. A knitting machine having, in combination, a needle carrier with needles thereon, a bed plate upon which said needle carrier is rotatably mounted, a standard adjustably mounted on said bed plate, a rocker frame pivoted to said standard, a sinker wheel equipped with sinker blades journaled to rotate upon said rocker frame and eccentric to the axis thereof and yielding means fast

- to said standard adapted to hold said rocker frame in position and prevent the same from rotating while said sinker blades are in operative engagement with said needles, 5 said yielding means also adapted to hold said rocker frame in position with said sinker blades out of engagement with said needles, whereby said sinker wheel, rocker frame and yielding means may be simultaneously 10 adjusted relatively to said needle carrier.
3. A knitting machine having, in combination, a needle carrier with needles thereon, a bed plate upon which said needle carrier is rotatably mounted, a standard adjustably mounted on said bed plate, a rocker frame pivoted on said standard, a sinker wheel equipped with sinker blades journaled to rotate upon said rocker frame and eccentric 20 to the axis thereof, an arm on said rocker frame, a stop and a flat spring on said standard, said spring being bent at its free end and adapted to bear against said arm upon opposite sides thereof alternately, 25 whereby said arm may be held against said stop or out of contact therewith, whereby said sinker wheel, rocker frame and spring may be simultaneously adjusted relatively to said needle carrier.
- 30 4. A knitting machine having, in combination, a needle carrier with needles thereon, a bed plate upon which said needle carrier is rotatably mounted, a standard adjustably mounted on said bed plate, a rocker frame, pivoted on said standard, a sinker wheel equipped with sinker blades journaled to rotate upon said rocker frame and eccentric 35 to the axis thereof, an arm on said rocker
- frame, a stop and a U-shaped flat spring, one leg of said U fastened to said standard, 40 the other leg of said U being bent at its free end and adapted to bear against said arm upon opposite sides thereof alternately, whereby said frame may be held against said stop or out of contact therewith, whereby 45 said sinker wheel, rocker frame and U-shaped flat spring may be simultaneously adjusted relatively to said needle carrier.
5. A knitting machine having, in combination, a needle carrier with needles thereon, 50 a bed plate upon which said needle carrier is rotatably mounted, a standard adjustably mounted on said bed plate, a rocker frame pivoted on said standard, a sinker wheel equipped with sinker blades journaled to 55 rotate upon said rocker frame and eccentric to the axis thereof, an arm on said rocker frame, a stop, a U-shaped flat spring, one leg of said U fastened to said standard, the other leg of said U being bent at its free 60 end and adapted to bear against said arm upon opposite sides thereof alternately, whereby said frame may be held against said stop or out of contact therewith, and a stationary stop arranged to engage the base 55 of said U-shaped spring, whereby said sinker wheel, rocker frame, stop and U-shaped flat spring may be simultaneously adjusted relatively to said needle carrier.

In testimony whereof I have hereunto set 70 my hand in presence of two subscribing witnesses.

WILLIAM T. BARRATT.
